Primary Examiner — Michael A. Pratt*Assistant Examiner* — Michelle E Wilson(74) *Attorney, Agent, or Firm* — Francisco A. Rubio-Campos; Apogee Law Group P.C.(57) **CLAIM**

I claim the ornamental design for a buffing pad, as shown and described.

DESCRIPTION

FIG. 1 is a top perspective view of an example of a buffing pad according to the invention;

FIG. 2 is a bottom perspective view of the buffing pad of FIG. 1;

FIG. 3 is a top plan view of the buffing pad of FIG. 1;

FIG. 4 is a bottom plan view of the buffing pad of FIG. 1;

FIG. 5 is a left/right elevational view of the buffing pad of FIG. 1, as these views are mirror images of each other; and, FIG. 6 is a front/rear elevational view of the buffing pad of FIG. 1, as these views are mirror images of each other.

1 Claim, 3 Drawing Sheets(56)
